[57] **CLAIM**

The ornamental design for a gable roof-like canopy, as shown and described.

DESCRIPTION

FIG. 1 is a perspective view of a gable roof-like canopy, the broken lines showing a table are for illustrative purposes only, and form no part of the claimed design;

FIG. 2 is a top plan view thereof;

FIG. 3 is an end view thereof;

FIG. 4 is a right side elevational view thereof;

FIG. 5 is a bottom plan view thereof;

FIG. 6 is a left side view thereof; and,

FIG. 7 is the opposite end view of FIG. 3.
